CLAIM

The ornamental design for a armrest cover, as shown and described.

DESCRIPTION

FIG. 1 is a front perspective view of a armrest cover, showing my new design therefor;

FIG. 2 is a top plan view of my new design for a armrest cover;

FIG. 3 is a front view thereof, the rear view being a mirror image;

FIG. 4 is a left side view thereof, the right side view being a mirror image; and,

FIG. 5 is a bottom view thereof.
